UNITED STATES PATENT OFFICE.

CHARLES M. BLACKMAN, OF BROOKLYN, NEW YORK, ASSIGNOR TO THE
S. H. WETMORE COMPANY, OF NEW YORK, N. Y.

DESIGN FOR A CAKE OF SOAP.

SPECIFICATION forming part of Design No. 27,864, dated November 16, 1897.

Application filed June 8, 1897. Serial No. 639,922. Term of patent 7 years.

To all whom it may concern:

Be it known that I, CHARLES M. BLACKMAN, a citizen of the United States, residing at Brooklyn, in the county of Kings and State 5 of New York, have invented and produced a new and original Design for a Cake of Soap or Toilet Pumice, of which the following is a specification, reference being had to the accompanying drawings, forming a part thereof. 10 Figure 1 represents a face view of the cake, showing the groove therein. Fig. 2 is an end view thereof.

The leading feature of my design consists of a cake of toilet pumice or soap having a 15 shallow groove or depression formed in the article across one of its faces, the groove being continued in the same plane out to the ends of the cake.

1 represents a cake shown in the drawings as being oval in general appearance. 2 represents the broad and open groove formed upon one of its faces, extending in the same plane to the ends of the cake. 20

What I claim as new, and desire to secure by Letters Patent, is— 25

The design for the toilet pumice or cake of soap substantially as shown and described.

In testimony whereof I hereunto affix my signature in the presence of two witnesses.

C. M. BLACKMAN.
